UNITED STATES PATENT OFFICE

WALTER M. HILL, OF HUDSON, COLORADO, ASSIGNOR, BY DIRECT AND MESNE ASSIGNMENTS, TO J. D. CANARY, OF LITTLETON, COLORADO

GRINDING MILL

Application filed August 28, 1928. Serial No. 302,523.

This invention relates to grinding mills and more particularly to mills of the type in which material fed onto a rotary impact element is thrown outwardly by centrifugal force against a relatively stationary impact wall and is thereby reduced in size.

It is an object of the invention to provide in a mill of the above described character, impact-members on the rotary element, which cause the material to be "batted" back and forth between the rotary and stationary elements, until it is completely and uniformly reduced to the required fineness.

A further object of the present invention is to provide in a mill in which a plurality of pulverizing units are disposed one above another to reduce material fed onto the upper unit in successive steps, a novel means for feeding material to the mill.

It is the aim of the improved feeding means to increase the capacity of the mill, to reduce wear, to assist in the production of a product of uniform size, and to eliminate the use of hoppers that are objectionable for many reasons and particularly because of their tendency to feed the material onto the rotary impact element in an arbitrary and uneven manner.

Another object resides in the provision of impact-members of novel construction, and of novel means for mounting the members upon the disks that constitute the rotary elements, and still further objects reside in details of construction as will be brought out in the course of the following description.

In the accompanying drawings in the several views of which like parts are similarly designated.

Figure 1 represents a vertical section through a mill of the improved construction,

Figure 2, an enlarged fragmentary section through one of the pulverizing units, as on the line 2-2, Figure 1,

Figure 3, a section along the line 3-3, Figure 2,

Figure 4, a horizontal section taken on the line 4-4, Figure 1,

Figure 5, a fragmentary plan view of one of the disks, showing a modified construction of the impact-members,

Figure 6, a section along the line 6-6, Figure 5,

Figure 7, a view similar to Figure 5, showing another modification of the impact-member,

Figures 8, 9 and 10, sectional views in the plane of Figure 1, showing modifications in the construction of the feed-element included in the invention,

Figure 11, a horizontal section on the line 11-11, Figure 8,

Figure 12, a similar section on the line 12-12, Figure 9, and

Figure 13, a horizontal section showing another modification of the distributing member.

The mill as shown comprises a plurality of pulverizing units of progressively increasing diameters, superposed one above another from the top of the mill at which the material is fed, to the bottom of the mill at which the product of the successive pulverizing actions is discharged. Each unit comprises a circular part of a shell 5 to which is fastened a correspondingly formed impact or breaker-ring 6, a disk 7 mounted to rotate about an axis coincident with that of the ring, and having its periphery spaced from the ring, and a series of blades 8 fastened at the periphery of the disk.

The shell 5 provides a housing of stepped form, and its horizontal surfaces at the top of each unit, are protected by lining plates 9. It is preferred to construct this housing in sections which are connected by bolts 10 in registering apertures of outwardly projecting flanges 12.

Beneath the housing is a discharge hopper 13 having a central opening 14 and provided with an outwardly projecting flange 15 for its support upon a suitable foundation.

The box 16 of a step-bearing in the vertical axis of the discharge hopper, is formed integral therewith by radial webs 17 and the box contains a roller bearing 18 and a series of washers 19 for the support of a vertical shaft 20 upon which the disks of the several pulverizing units are mounted for conjoint rotation. Another bearing 21 for the shaft, similarly constructed, is supported by legs 22

forming an integral part of a cover-plate 23 that closes the housing of the mill at the top thereof.

The box of the lower bearing is closed by a cap 24 and a lubricant may be supplied to the bearing while the mill is in operation, through pipes 25 and 26.

The disks 7 are fastened on the shaft by a key 27, and they are spaced from each other by collars 28. A nut 29 screwed upon a screw threaded portion of the shaft, reduced in diameter, serves to hold the disks against vertical displacement.

Immediately above the upper grinding unit 15 is a feed-chamber 30, the circular wall 31 of which may consist of a smooth lining of white iron fastened inside the corresponding upright part of the housing. The feed-chamber is smaller in diameter than the upper 20 grinding chamber in substantially the same ratio at which each grinding unit is larger than the one immediately above the same.

The wear ring 31 is not an essential and may be eliminated, or under certain conditions it may be corrugated as indicated in Figure 12.

Inside the feed chamber is a feed disk 32 which is spaced from the wall thereof and is supported upon the disk of the upper grinding unit by a collar 33. The feed disk is fastened on the shaft by the same key that holds the disks of the pulverizing units, and the aforementioned nut engages upon a washer 34 supported on the feed disk.

The top-plate 23 of the mill has one or more openings 35 through which material is fed into the feed chamber, and spouts 36 may be provided to direct the feed to the openings.

The feed disk functions to distribute the material supplied through one or more openings at the top of the housing, evenly and uniformly upon the disk of the upper pulverizing unit. The feed is effected by centrifugal force and overloading of any part of the disks of the pulverizing units as frequently occurs in the use of stationary hoppers, is entirely avoided. The rotating feed disk distributes the material evenly and entirely around the mill at all times during its operation. The capacity of the mill is thereby increased and a product of constantly uniform fineness is assured.

The feed plate may be flat as shown in Figure 1 of the drawings, or it may be provided with retarding means such as the concentric rings indicated at 46 in Figures 9 and 12, or radiating curved ribs shown at 47 in Figure 13.

The disk may also be provided with a circumferential flange or rim shown at 48 in Figures 8 and 11, in which case it will fill with material having its surface slope inwardly to the axis of rotation. The material distributed by the rotary motion of the disk,

will thus move across a bed of fine material held by the flange, which eliminates wear and promotes attrition. The material sliding toward the circumference of the feed disk at an upward angle, will be retarded and therefore be more evenly distributed.

In this connection, it will be understood that a similar result may be obtained by concaving the feed disk to the shape of a saucer, as illustrated at 49 in Figure 10, it being evident that any means for retarding the movement of the material across the feed disk will aid in effecting a better and more even distribution of the material around the mill.

The disks of the pulverizing units are each equipped with a plurality of blades that are preferably equidistantly, arranged at the peripheries of the disks. The blades extend radially of the disks and their outer ends which are in line with the peripheries of the respective disks, are toothed or corrugated as shown at 37. The drawings show three blades of different constructions and it is to be understood that other modifications may be made within the scope of the invention. The blade shown in Figure 2 is of sector-form and is secured to the disk by a counter-sunk machine bolt 38.

In order to hold the blade against side-wise movement, it has at its lower surface, a non-circular tenon 39 that fits in a correspondingly shaped mortise 40 in the upper surface of the disk.

The form of blade illustrated in Figure 7 differs from the one hereinabove described, only in that the tenon is omitted and in that two bolts are provided to rigidly secure the hammer in place on the disk.

The blade 41 illustrated in Figures 5 and 6, is toothed at opposite ends and it is fastened to the disk by means of a central bolt 42. When one end of the blade is worn, the blade may be turned about the bolt to bring the other toothed face in line with the periphery of the disk. It has been found in practice that the blades wear quickest at the forward end of their toothed faces with relation to the direction of rotation of the disk, and this being the case, the usefulness of the blade may further be prolonged by turning it upside down on the disk so that the opposite end of its working face is exposed to the abrasive action of the material under treatment. It will thus be observed that the blade can be adjusted to four different positions before its usefulness is at an end.

Another advantage of the arrangement of the blades on the disks of the pulverizing units as hereinabove described, is that the direction of rotation may be reversed, thereby bringing the opposite sides of the impact blades into action in case one side is worn away, without the necessity of changing the position of the blades on the disks.

The blade shown in Figure 5 is rigidly held

in its operative position by a lock consisting of block 43 fastened on the disk by a bolt 44 and having teeth that interlock with those at the inner end of the blade.

5 It is desirable that the number of blades on each disk is in ratio to the diameter thereof so that each larger disk carries more hammers than the smaller disk or disks above the same.

10 In the operation of the machine the material fed through the openings of the top plate falls on the feed disk 32 in the feed chamber 30 and is thereby uniformly distributed about the periphery thereof, as hereinintended.

15 It is to be observed that each disk is proportioned so that its periphery falls within the vertical planes of the inner ends of the impact-members of the next lower disk there-
20 by causing the material that passes downwardly through the annular passage of the feed chamber or through the annular passage of each upper pulverizing unit to fall upon the next lower disk in the zone within the
25 series of peripheral blades thereof.

The material fed upon the disk of each pulverizing unit moves outwardly by centrifugal force within the path of the blades which throw it violently against the toothed
30 breaker ring. The impact of the material with the teeth of the ring causes it to rebound against the teeth of the blades on the disk and the material is in this manner batted back and forth until it is reduced to a size that permits of its being drawn downwardly by the
35 suction produced in the operation of the mill, through the annular passage of the unit between the disk and the breaker ring, into the next lower unit where the operation is re-
40 peated.

The material thus subjected to a succession of pulverizing actions is gradually reduced to the desired fineness and finally discharged from the machine through the hopper 13.

45 The back and forth movement of the material between the blades and the breaker ring in the pulverizing units has been indicated in Figure 2 by the arrows 45.

The toothed blades, coacting with the sur-
50 rounding breaker rings, are adapted to ex-
tremely fine grinding and produce a material increase in the capacity of the mill over sim-
ilar machines employing blades or hammers,
the ends of which are smooth.

55 In mills of the last mentioned type, the material after having been thrown against the breaker ring would be discharged without further diminution into the next lower unit in a mixture of fine matter and large un-
60 ground particles.

In the present mill the toothed blades cause the material to be batted back and forth as indicated by the arrows 45, until it is uni-
65 formly reduced to the desired fineness, owing

to the constant movement of the hammers inside the relatively stationary ring.

The material being batted to and fro in the annular space between the rotating disk and the wall of the pulverizing chamber, is not only reduced by its forceful impacts with these parts, but also by the attrition of the oppositely moving streams as they cross one another.

70 The hammers may have one or more teeth, and owing to the fact that the material does not pass in a constant stream across the ends of the hammers as was the case where smooth-ended blades were used, the hammers are less subject to wear.

75 What I claim and desire to secure by Letters Patent is:

1. In a pulverizing mill, a pulverizing unit comprising a circular impact wall, a rotary disk spaced from the wall, blades reversibly mounted on the disk and having impact-ends one of which is at the periphery of the same, and means for locking said blades against lateral displacement.

80 2. In a pulverizing mill, a pulverizing unit comprising a circular impact wall, a rotary disk spaced from the wall, and blades reversibly mounted on the disk, each blade having opposite toothed ends, one of which is at the periphery of the disk.

85 3. In a pulverizing mill, a pulverizing unit comprising a circular impact wall, a rotary disk spaced from the wall, a blade reversibly mounted on the disk, the blade having opposite toothed ends, one of which is at the periphery of the disk, and means for locking the blade in place by engagement with the teeth at the inner end thereof.

90 4. In a pulverizing mill, a pulverizing unit comprising a circular impact wall, a rotary disk spaced from the wall, a blade reversibly mounted on the disk, the blade having opposite toothed ends, one of which is at the periphery of the disk, and a toothed block on the disk meshing with the inner teeth of the blade to lock the blade in place.

95 5. In a pulverizing mill, a plurality of pulverizing units increasing successively in diameter from the top of the mill and each including a circular impact wall, a disk spaced from the wall, and impact-members on the disk at the periphery thereof, the space of each unit being above the disk of the next lower unit, means for feeding material to the upper unit, a shaft on which the disks of the units are mounted for conjoint rotation, a discharge hopper below the lower unit, and a bearing for the shaft supported by the hopper.

100 6. In a pulverizing mill, a plurality of pul-
verizing units increasing successively in di-
ameter from the top of the mill and each in-
cluding a circular impact wall, a rotary disk spaced from the wall, and impact mem-
bers on the disk at the periphery thereof,

the space of each unit being above the disk of the next lower unit, means for feeding material to the upper unit, a shaft on which the disks of the units are mounted for joint rotation, a discharge hopper below the lower unit, a bearing for the shaft supported by the hopper, and a bearing for the shaft at the top of the mill.

7. In a pulverizing mill of the character described, a pulverizing unit, a circular feed chamber above the unit, and a rotary feed disk having means for retarding the movement by centrifugal action of material to said unit, and being peripherally spaced from the wall of the chamber.

8. In a pulverizing mill, a grinding chamber having a continuous circular wall and a feed-opening, and a rotary feed member in the chamber below the feed-opening and spaced from the wall, to impel material toward the wall by centrifugal force, the feed-member being adapted to oppose the outward movement by centrifugal force, of the material.

25 9. In a pulverizing mill, a grinding chamber having a continuous circular wall and a feed-opening, and a rotary feed member in the chamber below the feed-opening and spaced from the wall, to impel material toward the wall by centrifugal force, the feed-member having a material-retaining rim.

10. A pulverizing mill comprising a vertical shaft, horizontal grinding chambers disposed one above another whereby material 35 may descend by gravity from one to another, the chambers having toothed circular impact surfaces, horizontal rotary disks on the shaft and disposed in the chambers, and grinding members at the peripheries of the disks, 40 having teeth opposed to those of the impact surfaces, the teeth of the upper impact surface being disposed to direct material inside the grinding members on the lower disk.

11. A pulverizing mill, comprising a grinding chamber having a continuous circular wall and a feed opening, and a rotary feed member in the chamber opposite the feed opening and spaced from the wall, to impel material toward the wall by centrifugal 50 force, the feed member having upturned means to retard material crossing the member.

In testimony whereof I have affixed my signature.
